INKING PAD

William Van Prooyen, Jr., Ada, Mich.

Application January 24, 1949, Serial No. 429

Term of patent 14 years

(Cl. D74—1)

To all whom it may concern:

Be it known that I, William Van Prooyen, Jr., a citizen of the United States, residing at Ada, in the county of Kent and State of Michigan, have invented a new, original, and ornamental Design for an Inking Pad, of which the following is a specification, reference being had to the accompanying drawing, forming part thereof.

Fig. 1 is a plan view of an inking pad, showing the new design.

Fig. 2 is a side view of the same.

Fig. 3 is an end view of the same, and

Fig. 4 is a perspective view of the same.

My design for an inking pad is characterized by its elliptical shape with concave sides and curved in top all as illustrated on the drawing.

I claim:

The ornamental design for an inking pad, substantially as shown and described.

WILLIAM VAN PROOYEN, JR.
